UNITED STATES PATENT OFFICE.

ALBERT P. BROOMEML, OF YORK, PENNSYLVANIA.

SUBMARINE MINE.

940,506.

Specification of Letters Patent. Patented Nov. 16, 1909.

Application filed May 14, 1909. Serial No. 495,983.

To all whom it may concern:

Be it known that I, ALBERT P. BROOMEML, a citizen of the United States, and a resident of York, in the county of York and 5 State of Pennsylvania, have made certain new and useful Improvements in Submarine Mines, of which the following is a specification.

This invention is an improvement in submarine mines or torpedoes, and the invention has for an object to provide a novel method of placing the torpedo at the desired depth below the surface of the water and a novel construction whereby the mine 10 is so placed; and the invention consists in the novel method and construction, combination and arrangement of parts as will be hereinafter described and claimed.

In the drawings Figure 1 is an elevation 20 of the parts showing the torpedo and connected parts descending in the water. Fig. 2 is a similar view showing the parts with the anchor at the bottom, and the torpedo and connected parts ascending, and Fig. 3 is a similar view showing the torpedo in its 25 ultimate position and stopped in such position by coöperating parts, the auxiliary or gage float being shown as resting on the surface of the water. Fig. 4 is a vertical longitudinal section of the two part anchor 30 with the paying-out device connected therewith and also shown in section, a portion of the torpedo being shown in elevation. Fig. 5 is a side view of the two part anchor and 35 the paying-out device, the detent mechanism being shown in released position. Fig. 6 is an elevation of the opposite side of the paying-out device from that shown in Fig. 5, and illustrating the brake mechanism for preventing the paying-out device from operating 40 too freely. Fig. 7 is a detail perspective view of one of the keys for detachably securing the paying-out device to the anchor, and Fig. 8 is a detail side elevation partly 45 broken away, showing a modification of the detent mechanism illustrated in Fig. 5.

This invention relates to that class of torpedoes which are automatically placed at the desired depth below the surface after being launched from the vessel. Heretofore such torpedoes when launched are carried down by the anchor device and means are provided whereby the torpedo is checked or

stopped in its descent in its ultimate position. In other words, the torpedo is carried 55 down to its ultimate position and remains there, the anchor device ordinarily continuing its descent until it reaches the bottom of the sea or other water way.

My invention involves a new method and 60 includes sinking the buoyant torpedo to a point below its predetermined ultimate depth and permitting the said torpedo to rise from said lower point and limiting the extent of its rise so that it is placed in its 65 ultimate position by carrying it below said ultimate position and checking its ascending movement above said position when it reaches the desired level below the water surface. This is an important feature of my 70 invention, and in carrying out this feature of my invention I prefer to employ a supplemental or gage float which operates in the manner more fully described hereinafter to secure a stoppage of the torpedo as it ascends from its lower level to its desired ultimate level below the surface of the water.

In carrying out the invention I employ in the construction shown a torpedo A, a two part anchor B, a paying-out device C, and a 80 supplemental or gage float D, operating in connection with detent mechanism to restrain the operation of the detent when the gage float is submerged, and to permit said detent to check the movement of the paying-out device when the gage float reaches the 85 surface of the water.

From the foregoing it will be noticed that my invention includes in connection with a buoyant torpedo, means for sinking the 90 same, to a point below the predetermined level, means for automatically releasing the torpedo to permit it to ascend by its buoyancy, and means controlling the extent of the ascension of the torpedo. 95

The anchor B is a two part anchor, having a base B' which may be dished in its upper side to receive the lower end of the section B², which section B² slides relatively to the section B' and upon vertical guide pins 100 B³ secured to the section B' and operating in openings B⁴ in the section B², and provided with cam portions B⁵ which operate upon keys B⁶ when the section B² drops into the section B' and move the said keys B⁶ 105 laterally out of engagement with the de-

pending bars C' of the frame of the paying-out device C, thus releasing the said paying-out device and permitting the same to rise by the buoyancy of the torpedo A. The 5 frame C² of the paying-out device C has bearings for the shaft C³ of the drum C⁴, the said drum receiving a line E, which extends thence upwardly in connection with the upper section B² of the two part anchor.

10 In connection with the drum I provide a brake shoe C⁵ operating upon a surface C⁶, see Fig. 6 of the drawings, and actuated by a spring C⁷, whose tension may be adjusted by a screw C⁸ in order that the brake may 15 be set to prevent the drum from paying-out the rope too freely, as the paying-out device C ascends with the buoyant torpedo A as shown in Fig. 2 of the drawing. I also use in connection with the paying-out device a 20 detent in the form of a pawl F, operating upon a ratchet F', on the drum C⁴ and pressed normally into engagement with said ratchet by a spring F² whose tension may be adjusted by the bolt F³. This pawl F when 25 in engagement with the ratchet F', will stop the paying-out of the rope E, and thus check the ascent of the torpedo A. During the ascending movement of the torpedo A, the pawl F is held out of engagement with the 30 ratchet F' by the auxiliary or gage float D, which has a line G connecting it with the pawl F, so that the lift exerted by the buoyancy of the gage float D will operate as shown in Fig. 2, to hold the pawl F clear of 35 the ratchet F' so that the drum may be freely revolved without regard to the pawl F. While the pawl F and the ratchet F' are desirable in this connection, it is manifest other constructions might be employed, 40 and I might employ the construction shown in Fig. 8, in which a brake shoe H is arranged to operate upon a brake surface H' and may be pressed thereagainst with sufficient force to stop the paying out of the line 45 and to check the upward movement of the torpedo when the pull on the brake shoe by the gage float ceases as the said float reaches the surface of the water. I therefore, do not desire to be limited to any particular 50 detent mechanism as various forms of detent mechanism might be devised and arranged to be restrained by the operation of the gage float during the ascending movement of the said gage float.

55 As will be understood from Figs. 4, 5 and 6, the depending bars C' of the frame C² of the paying-out device are tapered gradually reducing toward their lower ends so that when the keys or bars B⁶ are adjusted out of 60 the openings C⁹ in the bars C' the paying-out device may freely rise from the two part anchor as it is lifted by the buoyancy of the torpedo A. I show the anchor as provided with a handle B' and removable pins I fit in sockets in the sides of the sections B² and 65 rest upon the upper edge of the side flange B⁸ of the section B', and support the section B² in the position shown in Fig. 4, preliminary to launching the mine in the water so the anchor can be rested upon the deck or 70 other support with the keys B⁶ in the position shown in Fig. 4, without displacing said keys by the movement of the sections B² along the cams B⁵. Of course, when the mine is about to be launched the pins I are 75 removed and the bottom section B' suspended by its bars B³ from the section B² of the two part anchor. A slot or slots B⁹ may be provided in the flange B⁸ of the section B', and a groove B¹⁰ be provided in the section 80 B² in register with the slot B⁹ for the introduction of a crow bar or other implement by which the section B² may be pried upwardly from the section B' when so desired. Encircling the drum C⁴ is a metal shield composed of two semicylindrical sections J, hinged at their upper ends at J' and bolted together at J², the said sections J being spaced apart sufficiently at their lower ends to permit the operation of the rope or cable, 85 and this casing or shield operates to prevent the rope from fouling in any way, and being hinged at J', the section J may be opened whenever desired to permit inspection of the incased parts. The gage float D, should ordinarily have a displacement of from one hundred to one hundred and fifty pounds, and may preferably be made with a tube D' running through it, through which the rope 90 D is passed and knotted at G' above the 100 float to give the desired distance between the gage float and the detent mechanism of the paying-out device, the length of the line G determining the depth of the torpedo A below the surface.

105 The operation will be readily understood from the foregoing in connection with the accompanying drawings. When the mine is launched it sinks toward the bottom with the parts in the position shown in Fig. 1. When the anchor strikes the bottom, the top section B² will drop down to the bottom piece B', and the cams B⁵ will push the bolts or keys B⁶ laterally outward and release the paying-out device which will be lifted by the buoyancy of the torpedo A, and the said torpedo A and the paying-out device will rise together with the gage float D which is above the said torpedo, and the buoyancy of this gage float D is sufficient to restrain the 110 detent so the drum can revolve paying out the rope A and permitting the ascension of the torpedo A to be continued so long as the detent mechanism is held out of operation. When the float D reaches the surface and ceases to exert its pull on the rope G, the 115 detent mechanism will be operated by the spring F² to stop the revolution of the drum 120

125

and stop the paying out of the rope E, and the torpedo will thus be stopped at the desired point below the surface of the water depending upon the length of the line G, 5 which connects the gage float D with the detent mechanism of the paying-out device. After planting the mines in the desired locations, the floats D will indicate just where each mine is planted, and will give the operator 10 a line on the work which has been done. After the planting is effected, a small boat can pass along the line of floats D, and the knots G' can be cut off letting the ropes G drop and the floats D can all be picked up 15 for subsequent use.

In operation it will be understood that when a harbor has been mined in expectation of an enemy the floats D may be permitted to remain on the distance ropes G to 20 indicate exactly the position of their respective torpedoes, and the floats can remain so attached until the enemy actually approaches and when it is desired to dispose of the floats a small boat can run along the 25 line of floats and cut off the knots and lift the floats as before suggested, or if there is not sufficient time for this, bullets can be fired into the floats allowing them to sink. The floats D are also useful in the event of 30 its being desirable to lift the torpedoes at any time, as the operator can take hold of the float and pull on its line G with sufficient force to raise the detent of the paying-out device, which will allow the rope on the 35 drum to unwind and the torpedo to come to the surface when it can be lifted into the vessel. The anchor can be then lifted out by the line E, as will be readily understood from the drawings. The torpedo or mine 40 proper A has sufficient buoyancy to lift the paying-out device in the operation before described. I have not described any specific form of torpedo or mine proper A, as any desired form of torpedo or mine may be 45 used in carrying out the invention as before described.

By the described construction, it will be noticed the torpedo is carried to the bottom and is then released and permitted to rise 50 and is stopped at the right point below the surface of the water by the throwing of the detent pawl into the ratchet of the drum, and this idea of stopping the mine at the desired point as it ascends from a lower 55 point is an important feature of my invention. I also regard as an important feature of my invention the provision of the gage float for determining the depth of a submerged torpedo, and I illustrate in the accompanying drawings a simple efficient 60 means for carrying out this feature of my invention.

I claim—

1. A submarine mine comprising a buoy-

ant torpedo, an anchor therefor, a paying-out device between the anchor and torpedo, and a float operating in connection with the paying-out device for regulating the ultimate depth of the torpedo. 65

2. A submarine mine comprising a buoyant torpedo, an anchor, a paying-out device between the mine and anchor, means for detachably securing the paying-out device in connection with the anchor and means for automatically detaching the paying-out 75 device from the anchor.

3. A submarine mine comprising a buoyant torpedo, an anchor below the same, a paying-out device between the anchor and the torpedo, and a gage float above the torpedo and operating upon the paying-out device whereby to regulate the ultimate depth 80 of the torpedo.

4. The combination with a buoyant torpedo, and an anchor therefor, of a gage float 85 above the torpedo, and means whereby the gage float may operate to regulate the ultimate depth of the torpedo.

5. A submarine mine comprising a buoyant torpedo, means for anchoring the same, 90 and a gage float above the torpedo and means whereby said float operates to regulate the ultimate depth of the torpedo.

6. A submarine mine comprising an anchor, a buoyant torpedo, a paying-out device 95 between the torpedo and anchor, a detent to operate upon the paying-out device, and a gage float connected with the detent and operating to restrain the same when the 100 said gage float is submerged.

7. A submarine mine comprising a buoyant torpedo, an anchor therefor, means for permitting the torpedo to ascend buoyantly from the anchor, and a gage float determining the extent of said ascent. 105

8. A submarine mine comprising a buoyant torpedo, an anchor therefor, a paying-out device between the anchor and torpedo, a gage float, and a cable connecting the gage float with the paying-out device, and means 110 operated upon by the gage float whereby the length of the cable will determine the ultimate depth of the torpedo.

9. A submarine mine comprising a buoyant torpedo, an anchor therefor, a paying-out device between the anchor and torpedo, 115 means for detachably connecting the paying-out device with the anchor, means for restraining the operation of the paying-out device, and a gage float for holding said restraining means out of operative position. 120

10. A mine comprising a buoyant torpedo, means for sinking the same to a point below its desired level, means for permitting the ascent of the torpedo from said point, and 125 means for automatically checking the ascent of the torpedo when its desired level is reached.

11. The combination of a buoyant torpedo, means for sinking the same to a point below the predetermined level, means for automatically releasing the torpedo to permit it to ascend by its buoyancy, and a gage float above the torpedo and controlling the extent of its ascension.
12. The combination of an anchor, a paying-out device having a line connected with the anchor, a detent for stopping the operation of the paying-out device, a gage float connected with said detent and adapted to restrain the same while the gage float is submerged, and a buoyant torpedo connected with the paying-out device and adapted to lift the same by its buoyancy, substantially as set forth.
13. In a submerged mine, the combination with a buoyant torpedo, of a two part anchor therefor, a paying-out device having a line connected with said anchor, means for securing the paying-out device to the anchor, and means for releasing said paying-out device from the anchor and adapted for operation by the relative movement of the parts of the anchor, substantially as set forth.
14. The combination in a mine of a paying-out device, an anchor therefor having laterally movable pins or bolts for securing the paying-out device, and cams for operating said pins or bolts to release the same from the paying-out device, substantially as set forth.
15. The combination of a submerged torpedo, an anchor below the same and from which the torpedo may be automatically detached and permitted to rise by its buoyancy, and means for automatically checking such ascension of the torpedo.
16. The method of placing mines herein described which consists in sinking a buoyant torpedo to a point below its predetermined ultimate depth, automatically releasing the torpedo and permitting said torpedo to rise from said point, and automatically limiting the extent of its rise.
17. The combination of a buoyant torpedo, a weight or anchor by which to sink said torpedo to a point below its predetermined level, means whereby to automatically detach the torpedo from the anchor, and permit the same to rise from said point, and means whereby the upward movement of the torpedo will be stopped when it reaches the desired level.
18. The combination of a buoyant torpedo, an anchor, means detachably connecting said anchor with the torpedo whereby the anchor may sink the torpedo to a point below the ultimate level of the torpedo, means for automatically detaching said connections whereby the torpedo may rise from the anchor, and means operated from the surface of the water whereby to effect the stoppage of the torpedo when it has reached its predetermined level.
19. The combination of an anchor, a buoyant torpedo, means connecting the torpedo with the anchor whereby the latter as it sinks will carry the torpedo with it, and means for automatically releasing the torpedo from the anchor whereby the torpedo may rise from the anchor.
20. The combination of an anchor, a buoyant torpedo, a paying-out device between the anchor and torpedo, and including a drum, a ratchet in connection therewith, and a pawl normally engaging said ratchet, and a gage float connected with said pawl, substantially as set forth.
21. The combination of an anchor, a buoyant torpedo, a paying-out device between the anchor and torpedo including a drum and a ratchet in connection therewith, a pawl, a spring pressing said pawl normally into engagement with the ratchet, means for varying the tension of said spring, and a gage float connected with the pawl and adapted to resist by its buoyancy the spring which normally presses the pawl into engagement with its ratchet.
22. The combination of an anchor, a buoyant torpedo, a paying-out device between the torpedo and anchor, a detent for restraining the operation of the paying-out device, a spring operating upon said detent, and a gage float connected with the detent and operating the same in opposition to its spring.
23. The combination of a buoyant torpedo, an anchor therefor, a gage float above the torpedo, and means whereby the gage float may operate to determine the ultimate depth of the torpedo without exerting a buoying lift thereon.
24. The combination with a submerged buoyant torpedo, of a supplemental or gage float by which to determine the depth of said torpedo, and means for retaining the torpedo at its determined depth, the said means being adapted to hold the torpedo at different distances above the bottom, substantially as set forth.
25. In a submerged mine the combination with a torpedo, and a paying-out device, of an anchor having two parts, means for connecting the paying-out device detachably with the anchor, and means whereby the relative movement of the parts of the anchor may operate to release the paying-out device.
26. In a submarine mine, an anchor having a base and a part or section above the base and movable relatively thereto, a paying-out device, a mine connected with said paying-out device, means for detachably connecting the paying-out device with the anchor, and means for releasing the paying-

out device from the anchor when the latter reaches the bottom.

27. The combination of a buoyant torpedo, an anchor, a connection between the anchor and torpedo and adapted to secure the torpedo at different distances from the anchor, and a gage float operating from the

surface of the water and automatically determining the ultimate depth of the torpedo.

ALBERT P. BROOME.
